COMBINATION MOUNT AND SHOULDER REST

John R. Bird, Framingham, Mass.

Application August 29, 1947, Serial No. 771,291

3 Claims. (Cl. 89—17)

(Granted under the act of March 3, 1883, as
amended April 30, 1928; 370 O. G. 757)

1

This invention may be manufactured and used by or for the Government for governmental purposes without the payment to me of any royalty thereon.

My invention relates to a combined mount and shoulder rest for use with recoilless rifles, rocket launchers, and the like. It includes a bipod of such design as to be readily attachable to the rear trunnion of the gun which, when folded, will form a shoulder rest for the operators in off-hand firing and when unfolded will support the rear chamber of the gun in prone firing, and a monopod contained in a handle member for attachment to the front trunnion of the gun to replace the existing handle and which may be used as an ordinary handle in off-hand firing but which when extended forms a supporting leg to combine with the bipod to provide a tripod for the gun when used in prone firing.

It is a principal object of my invention to provide a support for recoilless rifles, rocket launchers, and the like which includes a combination bipod to support the rear chamber of the gun for prone firing and form a shoulder support for the operator in off-hand firing, and a combination monopod which cooperates with the bipod to form a tripod support for the gun for prone firing and provides a comfortable handle for the operator in off-hand firing.

It is an important object of my invention to provide a support of the character described in which the bipod element may be readily attached to the present rear trunnion of a gun, and the monopod element is readily attached to the front trunnion to replace the existing handle.

It is a further object of my invention to provide in a support of the character described means for locking the legs of the bipod in extended position which will allow variation in both spread and cant thereof.

It is a still further object of the invention to provide means in the monopod element for adjusting the extendable length thereof to allow variation in elevation of the gun.

It is another object of my invention to provide a support of the character described which is relatively simple in construction, efficient in operation and inexpensive to manufacture.

Other objects and advantages of the invention will become apparent during the course of the following specification, and accompanying drawings, forming part of the specification, in which like numerals are used to designate like or similar parts throughout.

In the drawings:

2

Figure 1 is a perspective view of a recoilless rifle mounted on an embodiment of my invention, in condition for prone firing.

Figure 2 is an enlarged partial side elevation of the same in condition for off-hand firing, the bipod being folded to form a shoulder support and the monopod closed to form a handle.

Figure 3 is a plan view of the bipod element and its mounting clamp.

Figure 4 is a transverse section through the pivotal connection of mounting clamp and bipod, taken on the line 4—4 of Figure 3.

Figure 5 is a transverse section through the bipod cant means, taken on the line 5—5 of Figure 3.

Figure 6 is a vertical section through the monopod, the mounting clamp, internal screw, and part of the telescoping foot member being shown in elevation.

Figure 7 is a vertical section through the telescoping foot member.

Figure 8 is a transverse section through the locking means of the monopod.

Figure 9 is an enlarged detail of the ferrule engaging means on the monopod, and

Figure 10 is a section through the clamp member for securing the bipod legs when folded, taken on the line 10—10 of Figure 2.

Referring now in detail to the drawings, the numeral 11 designates generally a recoilless rifle provided with a tube 12, a rear chamber 13, a firing mechanism 14, a rear mounting trunnion 15, and a front mounting trunnion 16. Since the rifle 11 is well known in the art, it will not be further described.

The numeral 17 designates generally the bipod element of my invention, adapted for mounting on the rifle 11 by means of a mounting clamp 18 formed with a tongue 19 at one end arranged for pivotal engagement in a bifurcated portion of the rear trunnion 15 by means of a headed pin 20 attached to the bipod 17 by a chain 21 as shown in Figure 1, the chain being omitted in the enlarged detail of Figure 2 for clarity. The trunnion 15 is notched as shown at 22 to engage a screw 23 threadedly mounted in the tongue 19 to prevent displacement of the said pin 20 when the bipod is unfolded to provide support for the rifle 11. The other end of the clamp 18 is formed as a clevis 24 in which the bipod 17 is mounted.

The numerals 25 and 26 designate the respective legs of the bipod 17 arranged for mounting in the clevis 24 by means of a pivot bolt 27 provided with a nut 27a extending therethrough.

55 The said legs are arranged for guided pivotal

movement outwardly therefrom on a plate member 28 also mounted on the clevis 24 by the bolt 27, the legs 25 and 26 being each provided with a neck 29 formed integral therewith and having an opening therethrough to engage respective pins 30 which pass through segmental openings 31 in plate 28 and are biased against said plate by springs 32 when cap nuts 33 are tightened on the threaded ends of the said pins and secured thereon by the screws 34 which are threaded into suitable threaded bores in the pins 30. Means are thus provided for swinging the legs 25 and 26 outwardly on the pivot screw 27 and to adjust the legs individually to provide variation in both spread and cant thereof.

The legs 25 and 26 are generally tubular in shape and each said leg is bent uniformly upward from the horizontal to provide similar concave portions 17a in each said leg to permit the said legs to cooperate to form a suitable shoulder support for the gun when the said legs are folded against the tube 12 on pin 20. The said legs 25 and 26 are also each bowed outwardly intermediately their ends in opposite directions, as clearly shown in Figure 3, to provide a greater spread from their common center and provide increased bracing for the gun. Each said leg is provided with a ground-engaging shoe 35 at the free end thereof, and a small plate 36 having an upturned portion 37 is secured to each said end adjacent each said shoe 35 by welding or otherwise for a reason which will hereinafter become apparent. A piece of strip metal 38 arranged to secure a shoulder pad (not shown) is secured to each said leg 25 and 26 in the vertical concave portion thereof as shown in Figures 2 and 3.

The numeral 39 designates a clamp member arranged to be mounted on the underside of tube 12 by welding or otherwise. It is provided with a pair of spaced apart dependent ears 40, each said ear having a hole 41 therethrough in registry with the hole in the opposed ear, the space between said ears being adapted to receive the ends of the legs 24 and 25 when folded on the pin 20 and hold them therein by the engagement of the upturned portions 37 of plate 36 in the holes 41.

The monopod or handle 42 comprises a hollow tubular housing member 43 closed at one end by a bifurcated clamp 44 formed integral therewith. The clamp 44 is arranged to engage the front trunnion 16 between the ears thereof, there being openings through said ears to engage a plurality of screws or bolts 45 to secure the said trunnion rigidly therebetween. The housing 43 is provided with circumscribing threads adjacent its open end and provides housing for a screw member 46 having a head 47 at its end adjacent the closed end of said housing slidably engaging the inner walls thereof. The open end of housing 43 is also provided with a plurality of small dependent tongues 48 about its periphery for a purpose which will hereinafter become apparent. Screw member 46 is arranged at its other end with an integral knurled collar 49 about its outer periphery to provide a hand grip.

The numeral 50 designates an internally threaded ferrule adapted to threadedly engage the screw member 46 for translative movement therealong. It is provided with a plurality of radial projections 51 about its inner periphery, a taper 52 at one end, and a plurality of recesses 55 about its upper edge to engage the tongues 48 of the tubular member 43 and prevent rotation of the ferrule relative to said member.

The telescoping foot member 53 comprises a hollow tubular member 54 closed at one end by a ground engaging foot 55 and having a circumscribing collar 56 at its open end for sliding contact with the inner walls of screw member 46 when said foot member 53 is inserted therein. A spring 57 mounted in the said member 53 urges a push button 58 outwardly to provide a stop for the collar 49 when the member 53 is extended downwardly and a second spring finger 59 extending upwardly in the said member 53 is bent outwardly adjacent its free end to permit the said end 60 to impinge against the inner wall of the screw member 46 for the hold of the said foot member frictionally in collapsed position. A common mounting 61 is provided for the said springs 57 and 59. When it is desired to collapse the foot member 53, the push button is manually depressed until it no longer obstructs collar 49 and the foot member is at the same time pushed into housing 43.

As has been pointed out heretofore, the monopod 42 is extendible in length to allow variation in elevation through the telescoping action of the respective members relative to each other. In order to lock the said monopod in its adjusted position, a collar 62 threaded internally at its upper end for engagement with the threaded end of tubular member 43 is provided. The said collar is provided with an internal annular groove 63 for reception of the ferrule 50 and is internally tapered as at 64 for frictional engagement with the tapered portion 52 of the ferrule 50. The collar 62 is knurled about its outer periphery for ease in handling.

When the gun 11 is being used for off-hand firing the bipod 17 is folded upwardly against the tube 12, the legs being folded inwardly and held secure in the clamp 39 as heretofore described. The elements of the monopod 42 are pushed inwardly and held secure to form a handle by the collar 62. When the gun 11 is to be used for prone firing, the bipod is unfolded and adjusted for determined spread and cant, and secured in such adjusted position by means of the cap nuts 33. The monopod 42 is extended to the desired position by full extension of foot member 53, ferrule 50 is threaded on the screw member 46 until the determined extensible length is obtained, and the monopod locked in the adjusted position by means of the locking collar 62.

It is to be understood that the form herein shown and described is a preferred embodiment of the same, and that changes in the shape and arrangement of parts, and substitution of materials and equivalents, may be made within the scope of the subjoined claims without departing from the spirit of the invention.

Having thus described my invention, I claim:

60. A mount for a recoilless rifle or the like having a tube and front and rear mounting trunnions, comprising a clamp mounted in said rear trunnion for swinging movement about a pivot, a bipod, including a pair of substantially parallel-disposed legs carried by said clamp and responsive to the swinging movement of said clamp to move to and from a first position wherein said legs lie in a plane substantially parallel to the axis of said tube to form a shoulder support for said gun and a second position wherein said legs lie in a plane substantially normal to said axis, means on said bipod for guiding each said leg from and toward the other said leg to one of a plurality of selective positions relative to each 65 other to form a support for the rifle, including 70 a telescoping foot member having a hollow tubular member closed at one end by a ground engaging foot and having a circumscribing collar at its open end for sliding contact with the inner walls of a screw member when said foot member is inserted therein, a spring mounted in the said member urging a push button outwardly to provide a stop for the collar when the member is extended downwardly and a second spring finger extending upwardly in the said member is bent outwardly adjacent its free end to permit the said end to impinge against the inner wall of the screw member for the hold of the said foot member frictionally in collapsed position, a common mounting provided for the said springs, when it is desired to collapse the foot member, the push button is manually depressed until it no longer obstructs the collar and the foot member is at the same time pushed into the housing, a collar threaded internally at its upper end for engagement with the threaded end of the tubular member, the said collar is provided with an internal annular groove for reception of the ferrule and is internally tapered for frictional engagement with the tapered portion of the ferrule, the collar is knurled about its outer periphery for ease in handling.

means for locking said legs in a said selected position, a front member including a dependent extendible handle rigidly carried by said front trunnion, means telescopically carried within said handle for selectively adjusting the length of said front member, and locking means for maintaining said telescopic means in a selected position, said legs being curved intermediate the ends thereof to form a shoulder rest when said legs are in said first position.

2. The structure of claim 1 in which the dependent legs of the bipod and the handle cooperate to form a tripod to support the gun.

3. The structure of claim 2 in which the means for swinging the said legs from and toward each other includes a plate having a pair of oppositely directed segmental openings therein carried by said clamp, a pair of screws respectively carried by said legs and arranged for movement through said openings, and manually operated locking nuts carried by each said screw for locking the said legs in a selected position relative to each other.
